UNITED STATES PATENT OFFICE

FRANCIS L. ARENSBERG, OF PITTSBURGH, PENNSYLVANIA, ASSIGNOR TO VESUVIUS CRUCIBLE COMPANY, OF SWISSVALE, PENNSYLVANIA, A CORPORATION OF PENNSYLVANIA

PROTECTIVE DEVICE FOR USE IN HOT-METAL LADLES

Application filed July 1, 1929. Serial No. 375,099.

This invention relates to protective devices for use in hot metal ladles, and more particularly to devices for protecting the ladle stopper rod assembly from deleterious action of the contents of the ladle. It relates still more particularly to a device adapted to be loosely disposed about a ladle stopper rod assembly and to be movable up and down with respect thereto in accordance with the level of the contents of the ladle.

The usual type of hot metal ladle comprises a refractory lining surrounded by a layer of brick and having a metal exterior. Such a ladle has a bottom outlet through which molten metal contained therein is adapted to be drawn off, there being a stopper cooperating with the outlet to control the flow of the metal. The stopper is disposed within the ladle and has connected with it a vertically extending rod. Through suitable mechanism the rod and stopper are adapted to be raised and lowered to control the flow of the metal out of the ladle.

The stopper rod is customarily covered with protective material, such as clay, which shields it from the direct action of the molten metal. Slag forms on top of the metal in the ladle and such slag has a decidedly detrimental effect on the clay which surrounds the stopper rod. Particularly when the slag is basic in character it is very corrosive and eats away the clay, thereby greatly reducing the life of the protective means. This corrosive action has long been recognized but, so far as I am advised, no practicable means to decrease or eliminate it has heretofore been found.

I have distinguished above the stopper rod proper and the stopper rod assembly, comprising the rod itself and its protective clay covering. However, for simplicity I shall hereafter merely refer to the "stopper rod", which term, in both the specification and claims, shall comprehend both the rod alone and the assembly.

I provide in combination a hot metal ladle having a stopper and stopper rod, and a protective device adapted to be disposed between the rod and the slag on top of the metal contained in the ladle whereby to pro-

tect the rod from the deleterious action of the slag. I further provide a hollow slag-resistant protective device adapted to be disposed about the stopper rod of a hot metal ladle to protect the rod from the deleterious action of the slag on top of the metal. Other objects and advantages of the invention will become apparent as the following description of certain present preferred embodiments thereof proceeds.

In the accompanying drawings I have shown certain present preferred embodiments of the invention wherein

Figure 1 is a central vertical cross-section through a hot metal ladle;

Figures 2 and 3 are central vertical cross sections through certain forms of protective members; and

Figure 4 is a perspective view of still another form of protective member.

Referring more particularly to the drawings, reference numeral 2 designates generally a hot metal ladle having the usual refractory lining 3 surrounded by a brick or metal body 4. The ladle is provided at its bottom with a metal outlet 5 with which cooperates a refractory stopper 6. The stopper 6 has a central vertical hole 7 therethrough which is enlarged at the lower end, as shown at 8. A bolt having a stem 9 and a head 10 cooperates with the stopper to connect it with a rod 11, the bolt threading into the lower extremity of the rod, as shown in Figure 1.

The rod 11 is surrounded throughout substantially its entire length with protective clay sleeves 12 which have interlocking hubs and flanges, as shown in Figure 1. These sleeves, together with the stopper 6, effectively protect the rod 11 from the direct effect of the metal contained within the ladle.

The rod 11 is threaded at its upper extremity and has connected therewith by means of adjusting nuts 13 a lever 14 having a pivot 15 on a fulcrum 16 fixed to the ladle. Also fixed to the ladle is a lug 17 having pivoted thereto at 18 a lever 19. Pivoted to the lever 19 at 20 and to the lever 14 at 21 is a link 22. As is well known, the stopper is controlled by operation of the

lever 19, whereby the flow of metal from the ladle may be regulated.

Loosely disposed about the stopper rod and the protective sleeves 12 is a secondary protective device designated in Figure 1 by reference numeral 23. As shown in that figure, the device 23 comprises merely a hollow cylinder whose internal diameter is substantially greater than the external diameter of the sleeves 12. This permits free movement of the protective device 23 up and down with respect to the stopper rod.

The protective device 23 is made of slag-resistant material. It may be of graphite or of a graphitic construction or of any other suitable slag-resistant material such as the heavier refractories, chromite, zircon, or combinations thereof in suitable proportions. The function of the protective device 23 is that it shall protect the clay sleeves 12 from the deleterious action of the slag which is on top of the metal in the ladle.

The specific gravity of the protective device 23 is less than that of the contents of the ladle, so that the device will float on the molten metal and will rise and fall in accordance with the rise and fall of the surface thereof. Inasmuch as the slag always forms on top of the metal in the ladle, being of less specific gravity than the metal, and inasmuch as the protective device 23 also floats on top of the metal, it follows that the protective device is at all times interposed between the layer of slag and the clay sleeves 12 surrounding the rod 11. This is true irrespective of the height of the metal in the ladle. As the metal rises, the protective device also rises, and as the metal falls, the protective device falls with it. Therefore, the slag is prevented from coming in contact with the clay sleeves, thus protecting them from the deleterious or corrosive action of the slag.

The size and shape of the protective device may be varied according to circumstances. Its diameter may be greater or less as compared with the diameter of the device 23 shown in Figure 1, but it is preferred that the internal diameter of the protective device be only sufficiently greater than the external diameter of the clay sleeves 12 to permit free movement of the protective device up and down within the ladle. Likewise the specific gravity of the protective device may be varied, depending upon the materials used for its construction, and its length will be so proportioned with respect to the specific gravity that the top of the device will extend upwardly to a sufficient extent to protect the clay sleeves from the slag. In Figure 1 the surface of the metal 24 is designated by the line L, the slag being designated by reference numeral 25. The protective device 23 floats upon the metal 24, and due to its less specific gravity projects upwardly a substantial distance above the line L and hence through the

layer of slag 25. The protective device will always be so proportioned that its upper extremity will extend well above the slag layer under normal conditions of operation. Although at times the surface of the slag may become hard by cooling in the air and thus tend to "scaffold" or become viscous in cooling, yet the conductivity of the protective device 23, particularly if it is of graphitic construction, is sufficient to keep the slag practically as hot as the molten metal, and therefore the slag should not hang at the top of the ladle, but should come down with the steel. If, however, the slag should become viscous and hold the protective device so that it does not move easily, the effect of the protective device will not be lost inasmuch as the slag is always in intimate contact with the steel and, therefore, the slag will fall with the level of the steel and carry the protective device with it, even though the protective device were retarded in movement by the viscosity of the slag.

In Figure 2 is shown a form of protective device in which the device is tapered toward its lower extremity in order to reduce its weight and therefore insure projection of a sufficient portion of it above the level of the molten metal proper that the function of the protective member will not be lost.

In Figure 3 is shown a form of protective member having a tapered lower portion and a rounded interior. The purpose of rounding the interior is to reduce the friction and therefore prevent hanging of the protective device on the sleeves 12 in case the device becomes slanted or shifted. There are no sharp corners or edges to catch on the clay sleeves 12.

In Figure 4 is shown a protective device 26 provided at its bottom with openings 27 so that when the ladle is being emptied, the protective device will not interfere with the flowing out of the last of the metal therein. The metal flows through the openings 27 and thence out the outlet 5 of the ladle, even though the protective device is resting on the bottom of the ladle.

While I have shown and described certain present preferred embodiments of the invention, it is to be distinctly understood that the same is not limited thereto but may be otherwise variously embodied within the scope of the following claims.

I claim:

1. In combination, a hot metal ladle having a stopper and stopper rod, and a protective device adapted to be disposed between the rod and the slag on top of the metal contained in the ladle whereby to protect the rod from the deleterious action of the slag.

2. In combination, a hot metal ladle having a stopper and stopper rod, means covering the rod to protect it from the metal contained in the ladle, and a secondary protec-

tive device adapted to be disposed between the rod and the slag on top of the metal.

3. In combination, a hot metal ladle having a stopper and stopper rod, and loosely fitting protective means about the rod adapted to move up and down in the ladle in accordance with the level of the contents thereof.

10 4. In combination, a hot metal ladle having a stopper and stopper rod, and a sleeve about the rod adapted to float on the fluid contents of the ladle with a portion of the sleeve substantially lower than the surface of the fluid contents of the ladle.

15 5. In combination, a hot metal ladle having a stopper and stopper rod, and a protective device of less specific gravity than the metal in the ladle and loosely disposed on the rod.

20 6. In combination, a hot metal ladle having a stopper and stopper rod, and a loosely mounted slag-resistant protective device adapted to be disposed between the rod and the slag on top of the metal.

25 7. In combination, a hot metal ladle having a stopper and stopper rod, and a slag-resistant sleeve about the rod, such sleeve having a specific gravity less than that of the fluid metal in the ladle.

30 8. In combination, a hot metal ladle having a stopper and stopper rod, and a slag-resistant sleeve loosely fitting the rod and adapted to float on the metal in the ladle.

35 9. A hollow slag-resistant protective device adapted to be disposed about the stopper rod of a hot metal ladle to protect the rod from the deleterious action of the slag on top of the metal.

40 10. A hollow graphitic protective sleeve for use about the stopper rod of a hot metal ladle to protect the rod from the deleterious action of the slag on top of the metal.

45 11. A protective device for ladle stopper rods, comprising a hollow slag-resistant member whose lower portion is provided with means directing the flow of hot metal therepast and out of the ladle.

50 12. A protective sleeve for ladle stopper rods, comprising a body portion having metal pouring openings in its walls.

In testimony whereof I have hereunto set my hand.

FRANCIS L. ARENSBERG.
